Dec 1352

G. H. Brown of New York N.Y.
Letter Patent No 1352, Dated Dec 18 1860

The schedule referred to in these Letter Patent and making part of the same

To all whom it may concern:

Be it known that G. H. Brown, of the City, County and State of New York, have invented or produced a new and Original Design for a Rolling Iron Shutter, and I do hereby declare that the following, is a full, clear and exact description thereof, reference being had to the accompanying drawings, making a part of this Specification, in which,

Figure 1, is a section taken transversely through three of the slats which form the shutter, showing the configuration of the same.

Figure 2, is a view of the outside surface of figure 1.

Similar letters of reference indicate corresponding parts in both figures.

The character of the design consists in forming each slat with a bead or convex surface extending longitudinally from end to end of the slat on one edge a longitudinal convex depression on the opposite edge, and a curved elevation in the middle; thus when two or more of these slats are brought together so that one edge of one slat will lay over the other edge of the next slat, a rolling face or surface will be produced, which in a cross section, taken at any point through the slats, will give a design or configuration of alternate long and short curves or large and small curved elevations and depressions, which will present a neat and handsome appearance and give a finished surface to the shutters, as will be seen from the following description and the accompanying drawings.

In the drawings the slats A, A, A, are represented when put together in the usual manner so that the edge of one slat will overlap the edge of the other slat. Each slat has a narrow concave surface (outside) formed at a, on one edge and a narrow convex surface (outside) formed at

2

Wes. 1352

b, on the opposite edge. The middle or intermediate portion c, of each slat is concave on its outside surface as clearly represented in the drawing figures 142. In putting, these slats A, A, A, or any number of them, together, the concave edge b, of one slat is lapped over the concave edge of another slat, thus producing an outside surface composed altogether of rolling elevations and depressions which are alternately wide and narrow. The highest point of the middle curve c, may be either above or below the plane of the short curve b.

What I claim as new and desire to secure by Letters
Patent, is:-

The design or configuration of the rolling iron shutter substantially, as herein described and represented.
